His Attorney

UNITED STATES PATENT OFFICE.

ROMAN LUKSTAT, OF PHILADELPHIA, PENNSYLVANIA.

TOY.

1,157,166.

Specification of Letters Patent. Patented Oct. 19, 1915.

Application filed July 1, 1915. Serial No. 37,458.

To all whom it may concern:

Be it known that I, ROMAN LUKSTAT, a subject of the Czar of Russia, residing at Philadelphia, in the county of Philadelphia and State of Pennsylvania, have invented 5 certain new and useful Improvements in Toys, of which the following is a specification.

My invention relates to improvements in 10 toys, and more particularly to an improved toy wind mill, the object of the invention being to provide a toy wind mill in which the wind mill is caused to revolve by the movement of a cord or other flexible device.

15 A further object is to provide a toy of the character stated which may be manufactured and sold at an extremely low price, and which will amuse and entertain.

With these and other objects in view, the 20 invention consists in certain novel features of construction and combinations and arrangements of parts as will be more fully hereinafter described and pointed out in the claims.

25 In the accompanying drawings: Figure 1 is a view in front elevation illustrating my improved toy. Fig. 2 is a view in longitudinal section on the line 2—2 of Fig. 1, the wind mill shaft and coöperating parts being shown in elevation, and Fig. 3 is a fragmentary view in section on the line 3—3 of Fig. 2.

30 1 represents a casing which is so shaped as to represent a mill, that is to say it is of general rectangular shape in horizontal section, is of greater length than breadth, and is provided with a hip roof 2, composed of two sections or plates which are preferably removable for access into the interior of the 35 casing. In the upper end of the casing, a shaft 3 is mounted. This shaft extends through the front and rear walls of the casing and is held against longitudinal movement by transverse pins 4, projected 40 through the shaft as shown clearly in Fig. 2. On the outer end of the shaft, a toy wind wheel 5 is secured, and consists of any number of blades or vanes 6 secured to a central head 7 on shaft 3.

45 50 8 represents a drum loosely mounted on shaft 3, and 9 is a coiled spring located around shaft 3, secured at one end to the casing 1, and at its other end to the drum 8. This spring serves the double function of 55 forcing the drum toward the front wall of the casing, and also operates to turn the

drum in one direction as will hereinafter appear. A ratchet clutch 10 is secured to the forward face of drum 8, and engages a pin 11 on shaft 3, the parts being held in engagement by the spring 9.

12 represents a cord or other flexible device which is secured at one end to the drum 8, is wound around the drum, and extends through an opening 13 in the bottom of 65 casing 1, and a button or other hand hold 14 is preferably provided on the end of the cord. While I shall hereinafter refer to this part 12 as a cord, it is to be understood that I use this term in the broad sense to 70 cover any flexible device adapted for the purpose.

The operation is as follows: The casing 1 is held in one hand, while the cord 12 is given a downward pull, causing the drum 8 75 to revolve and turn shaft 3 by reason of the engagement of ratchet clutch 10 with pin 11. When the end of the pull is reached, the momentum of the shaft and wind wheel will cause the same to turn beyond the movement 80 imparted by the drum, and this is permitted by reason of the ratchet clutch 10, which allows the pin 11 to ride freely in one direction. This pull on the cord also operates to 85 wind or contract spring 9, so that when the cord is released, the spring will turn the drum in the reverse direction to wind the cord thereon, and this movement is also permitted by the ratchet clutch, so that the shaft is turned only in one direction, and is 90 free to revolve in the other direction to the full force of the momentum imparted by the drum.

Various slight changes might be made in 95 the general form and arrangement of parts described without departing from my invention, and hence I do not limit myself to the precise details set forth, but consider myself at liberty to make such changes and alterations as fairly fall within the spirit 100 and scope of the appended claims.

Having thus described my invention, what I claim as new and desire to secure by Letters Patent is:

1. A toy of the character described, comprising a casing, a shaft mounted in the casing and projecting therefrom, a toy wind mill secured to the outer end of the shaft, a drum loose on the shaft, a cord secured to 105 and wound upon the drum, said cord projecting from the casing, a ratchet clutch connecting the drum and the shaft, and elas-

tic means connected to the drum and adapted to turn the same in one direction, substantially as described.

2. A toy of the character described, comprising a casing, a shaft mounted in the casing and projecting therefrom, a toy wind mill secured to the outer end of the shaft, a drum loose on the shaft, a cord secured to and wound upon the drum, said cord projecting from the casing, a ratchet clutch connecting the drum and the shaft, and elastic means holding the ratchet clutch in operative engagement and operating to wind the drum in one direction, substantially as described.

3. A toy of the character described, comprising a casing, a shaft mounted in the casing and projecting therefrom, a toy wind mill secured to the outer end of the shaft, a drum loose on the shaft, a cord secured to and wound upon the drum, said cord projecting from the casing, a ratchet clutch connecting the drum and the shaft, elastic means connected to the drum and adapted to turn the same in one direction, said elastic means comprising a coiled spring located around the shaft, secured at one end to the casing, and at its other end to the drum, substantially as described.

4. A toy of the character described, comprising a casing, a shaft mounted in the casing and projecting therefrom, a toy wind

mill secured to the outer end of the shaft, a drum loose on the shaft, a cord secured to and wound upon the drum, said cord projecting from the casing, a ratchet clutch connecting the drum and the shaft, elastic means holding the ratchet clutch in operative engagement and operating to wind the drum in one direction, said elastic means comprising a coiled spring located around the shaft, secured at one end to the casing, and at its other end to the drum, substantially as described.

5. A toy of the character described, comprising a casing, a shaft projecting through the casing, a toy wind wheel on the outer end of the shaft, a drum mounted loosely on the shaft, a cord wound upon and secured to the drum, said cord projecting from the casing, a pin on the shaft in the casing, a ratchet clutch carried by the drum and engaging the pin, and a coiled spring located around the shaft, secured at one end to the casing, and at its other end to the drum, substantially as described.

In testimony whereof I have signed my name to this specification in the presence of two subscribing witnesses.

ROMAN LUKSTAT.
